UNITED STATES PATENT OFFICE.

ENOCH LOUIS LOWE, OF SAN FRANCISCO, AND JAMES MICHAEL MEIGHAN,
OF GROVELAND, CALIFORNIA.

TRACK-BRAKE FOR RAILWAY-CARS.

SPECIFICATION forming part of Letters Patent No. 660,645, dated October 30, 1900.

Application filed March 23, 1900. Serial No. 9,873. (No model.)

To all whom it may concern:

Be it known that we, ENOCH LOUIS LOWE, residing at San Francisco, in the county of San Francisco, and JAMES MICHAEL MEIGHAN, residing at Groveland, in the county of Tuolumne, State of California, citizens of the United States, have invented certain new and useful Improvements in Track - Brakes for Railway-Cars; and we do hereby declare the following to be a full, clear, and exact description of the invention, such as will enable others skilled in the art to which it appertains to make and use the same.

Our invention has reference to improvements in track-brakes for railway-cars and tramways, and it consists in certain novel features of construction, which will be herein-after fully described in the specification and clearly pointed out in the claims.

The object of the present invention is to provide an efficient, durable, and practical track-brake for railway-cars and which can be employed for ordinary use and at the same time be adapted for emergencies when it is required to stop a car almost immediately to avoid accidents or for other purposes.

The peculiar construction of our improved track-brake lies in its automatic operation when a brake-shoe contacts a railway-track or other stationary surface when a car is in motion.

It consists of a brake block and shoe having their contacting surfaces inclined, the opposite side of the shoe being parallel with the railway-track. The block and shoe are automatically adjustable relative to their inclined surfaces through the medium of links and an elastic connection for keeping the inclined surfaces of the block and shoe always in contact. The brake-block is provided with a standard, which is adjustably secured in a hanger bolted to a car-frame. This standard supports all of the brake mechanism proper through the medium of a spring at the free end of the standard and an adjustable nut secured thereon. The brake is operated by suitable devices under the control of a motor-man. Adjacent to the brake-block and secured to the standard is a collar for receiving the thrust of a pair of rollers which are pivoted to the free arms of a bell-crank lever and

fulcrumed to ears projecting from the lower portion of the hanger. When a car, but more particularly a street-car, has reached the terminus of its route, the opposite end of the car serves as the front end for the return trip, and consequently the present braking mechanism has to be reversed one hundred and eighty degrees, so that it will be operative. To accomplish these results, we employ a gear-wheel working loosely on the standard of the brake-block, this gear-wheel having a spline and groove in the standard. Consequently the gear-wheel remains stationary relative to the vertical movement of the standard; but when the gear-wheel is rotated one-half its circumference through the medium of a rack the standard also revolves with its braking mechanism. By this means of reversing the brakes we get the benefit of four brakes on one car. Otherwise we would be using only two brakes if they were not reversed. This reversing mechanism can be operated automatically when employed on a steam-railroad by means of cams arranged on the inside of the car-wheels, thus reversing the brakes when the cars are reversed; but to adapt our invention to steam-roads it is not advisable to reverse them by any means, as a single block with opposing inclines and a single shoe or separate shoes will allow the braking mechanism for steam-roads to work automatically without reversing the same. For street-car service, where the room is limited, the reversing mechanism is preferable, as the motor-man merely pushes a lever on the platform of the car, when the brakes are reversed automatically in one direction by suitable spring mechanism and in the opposite direction by a simple lever mechanism.

Figure 1 represents a vertical longitudinal section of a car - truck with our improved device thereon and the accompanying mechanism for operating the same. Fig. 2 represents a plan of a car-truck with our improved brake mechanism thereon. Fig. 3 represents the track-brake secured to a hanger. Fig. 4 represents the device in section and viewed from the opposite side. Fig. 5 represents the device in end elevation and in contact with a car-rail. Fig. 6 represents a plan of the device. Fig. 7 represents a sectional plan of

the device, taken immediately under the hanger. Fig. 8 represents a shoe and brake-block in detail, the latter supported by rollers. Fig. 9 is an end elevation in detail of 5 the shoe detached from its links, with a roller resting on its inclined top. Fig. 10 represents a non-reversible track-brake for operating in opposite directions, but supplied with independent shoes. Fig. 11 represents a 10 somewhat similar device with the shoe integral. Fig. 12 is similar in construction to that shown in Fig. 11, the device being in an operative position, the shoe contacting a rail.

Our improved device is attached to a hanger 15 B. The hanger is provided with a depending hollow body B' for the reception of a movable standard d. Said standard is integral with a brake-block D. The upper end of said standard is screw-threaded and bears a 20 nut d' thereon. Said nut is for adjusting the wear of the brake and also for supporting the brake in its elevated position through a spring a.

The block D, previously referred to, is inclined on its bottom and is parallel with a similar inclined surface on a shoe C. Said inclined surfaces are held in elastic contact through the medium of a spring l, rod k, pins e, and links E, respectively.

30 w is a plug which is screw-threaded in the face of the block D for assembling the spring and pin previously referred to.

The shoe C is provided with a stop c' and an adjusting-screw c, the latter for regulating the travel of the block D and also for compensating for the wear of the rubbing-block C' in part. Said rubbing-block C', which is secured in the shoe E, takes up all the wear in consequence of the travel on a 40 railroad-track. These rubbing-blocks can be made of any desired material, such as cement, leather, cast-iron, wood, or indurated fiber.

It must be obvious to those skilled in railroads that the only expense incurred with our 45 improved track-brake is that of replacing a worn-out shoe.

Secured to the lower portion of the standard d is a collar F, having a large surface for 50 supporting a pair of rollers G, each roller being on opposite sides of the standard d and secured to a bell-crank lever, which is provided with two arms g, carrying a shaft h, said shaft being supported by ears f, integral 55 with the hanger-body B'. Secured at one end, or it may be both ends, of said shaft h is a curved lever H for operating the braking mechanism through other devices, which will hereinafter be more fully set forth.

60 Mounted on the upper end of the hanger-body B' is a spur gear-wheel I, which engages a rack J, said rack being secured by caps b to the hanger B. Said gear-wheel I is held in position by the spring a, previously referred to, and envelops the standard d and is 65 prevented from turning by means of a spline i, which engages a long groove d' in said

standard, (see Fig. 4,) and as the standard is reciprocated vertically it plays through the gear-wheel I, the latter being stationary. 70 When the gear-wheel revolves, it carries the standard with it through the medium of the spline and groove, and consequently all the braking device attached to said standard. The movement of the rack J is limited by the 75 bar K and head K', (see Fig. 2,) carrying the gear-wheel I only one hundred and eighty degrees, which revolves the brake-shoe immediately over the track when necessary to propel a car in the opposite direction. 80

In Fig. 8 friction-rollers 21 are shown which revolve in the bearings formed in the block D. Leading to each roller are oil-ports 22. (Shown in dotted lines.) The sides of the shoes are provided with flatings 23 for holding the brake-blocks in place. The brake-levers H, previously referred to, are connected to rods 9, chains 10 and 15, and also to pulleys 11 and 12, respectively, the latter being secured to the vertical-shaft 14, which 90 extends to the brake-handle.

When the rear end of a car is employed for traveling in an opposite direction, which will then be considered the front end, the brake mechanism will then have to be reversed, and 95 to accomplish this the racks J revolve the gear-wheels I one hundred and eighty degrees through the medium of the rods j, connected to heads k' on said racks and reach-bars K and K', respectively. Secured to the 100 bar K' are chains s, which connect to a bar r'. Said bar is pivoted to a short arm r, which forms part of an arm R, the latter being secured to a vertical shaft r'', having an operating-lever thereon for the motorman to manipulate the device. Bar K is held against the rigid stop m by means of springs L. When it is necessary to reverse the brakes, the shaft r'' is turned in the direction of the 110 hands of a watch, when it assumes the position shown in dotted lines, having the bar r' beyond the center of the vertical shaft r'', thus locking said bar against the tension of spring L. When it is necessary to reverse 115 the brake-shoes in the opposite direction to that shown in dotted lines, the arm R is thrown in the position indicated in full lines (see Fig. 2) by means of the springs L pulling the bar K tightly against the stops m, previously referred to. When bar K' is moved to 120 the right, it contacts spring-stops N, which yield to allow the short arm or lever r to be carried, with its connecting-rod r', slightly beyond the center of the vertical shaft r'', (shown in dotted lines,) when a slight backward movement takes place with the rods r'. The springs P, which envelop the guide-rod 125 O, pivoted to the lever N at o, press against said lever and guide-block p, thus holding the brake-shoes in alignment with the tracks. Lever N is fulcrumed at n and is provided with a stop n' for the purpose, as shown.

This invention is for putting the brakes on gradually when a car is running in the ordinary

nary manner, and it can be so manipulated for stopping a car almost instantly in case of an emergency, as previously stated. We provide a spring 19, bearing against a plunger 18, resting in a cavity formed in the brake-block D. Said plunger contacts the adjusting-screw c. When the brake is applied by forcing down the standard d and brake-block D through the medium of the lever H, the shoe C contacts the car-track, and as the car is moving in the direction of the adjusting-screw c the brake-block D rides up the incline on the shoe C toward and against said adjusting-screw. While said shoe is slipping on the car-track when the brake is first applied, the plunger 18 is being forced against the tension of the spring 19, and as the brake-block continues to ride farther toward the adjusting-screw c said shoe is forced more firmly against the car-track, which is in contradistinction to the old style of wheel-brakes, where the motorman must pull the brakes harder and harder to stop his car. With our improved brake the motorman puts the brake on lightly, as the spring 19 allows the block D to ride up the incline of the shoe C, said shoe pressing harder upon the car-track as the plunger 18 moves farther into the recess in the block D. Consequently the motorman gradually releases his brake to prevent too sudden a stop. If the brake were put on hard, it is obvious that the car would stop immediately, as the block D would wedge on beginning to move up the incline on the shoe C, the spring 19 having no retarding effect on the block D. As the block D rides up the incline on the shoe C the links E follow the shoe C, as the slot a' admits of the upper pin e being pulled downward through the medium of the spring l and plunger k. The torsional spring 25, (clearly shown in Fig. 7,) which envelops the shaft h, will allow a certain tension being put on said spring by the levers H, and consequently the resilience of the springs will extend to the brake-shoes, thus regulating the pressure on the car-tracks. By this means any unevenness of the car-rails where they are connected will not injure the brake, as the springs 25 aforesaid will act as a cushion and will allow the brake-shoes to ride over any defective rails or obstructions.

Referring to the track-brakes with double shoes C⁴ and C⁵ and a single block D⁸, (shown in Fig. 10,) this device is adapted for steam-railroads and has a double incline, so that it can be operated in opposite directions without reversing the shoes. It is provided with stops 27 to limit the movement of the shoes, but more especially the shoe that is not in use when the brake is in an operative position. We employ a double set of operating-levers H and H' and which are fulcrumed to ears f and f', respectively. The rollers G are provided with two sets of arms g and g', whereby they can be operated by either of the levers H and H', according to the direc-

tion in which a car is running. The arm g is provided with a slot g² to compensate for the radial movement of said arms when in operation. In Figs. 11 and 12 the block D⁸ is in one piece and also the shoes C⁴ and operates in a manner similar to the device shown in Fig. 10. Fig. 12 shows the device in an operative position, with the shoe C⁴ resting on a railroad-track and the block D⁸ forced upward on one side of the incline of said shoe C⁴.

We do not confine ourselves to the exact construction shown, as the incline of the shoes and brake-blocks can be an arc of a circle or of any other contour without departing from the spirit of our invention.

Having described our invention, that which we desire to claim by Letters Patent of the United States is—

1. A track-brake which may be operated in opposite directions, provided with a shoe having an inclined top for engagement with a brake-block which has a corresponding incline on the bottom thereof, and the means for holding said inclines in movable contact when operating the same on a railway-track, in combination with an adjusting-screw for regulating the forward movement of said brake-block, for the purpose as shown.

2. A track-brake which may be operated in opposite directions, provided with a shoe having an inclined top for engagement with a brake-block which has a corresponding incline on the bottom thereof, and the means for holding said block movably in contact with said shoe when operating the same on a railway-track, in combination with an adjusting-screw for regulating the forward movement of said brake-block, and a spring and plunger within said brake-block and contacting said adjusting-screw for the purpose as shown and described.

3. A track-brake which may be operated in opposite directions, consisting of two inclined surfaces in contact on a brake-block and shoe movably tied together by yielding links, in combination with an adjusting-screw and a plunger within said brake-block operating through the medium of a spring contacting said plunger, for the purpose as shown and described.

4. A track-brake provided with a shoe having an inclined top for engagement with a brake-block, which has a corresponding incline on the bottom thereof and the means for holding said inclines in movable contact when operating the same on a railroad-track in combination with an adjusting-screw for regulating the forward movement of said brake-block, and a plunger contacting said adjusting-screw located within a brake-block and having a standard secured to said brake-block for operating a track-brake for the purpose as shown and described.

5. In combination with a track-brake, a shoe having an inclined upper surface for receiving the thrust of a brake-block, said brake-

block having a corresponding incline on its lower surface for contacting the incline on said shoe, links secured to said shoe and brake-block by pins, the upper pin playing in an elongated opening and contacting a pin or plunger, said pin held in a movable position by a spring resting under said pin for allowing an elastic movement to the brake-shoe and brake-block when contacting a railway-track, for the purpose as specified.

6. In combination with a track-brake, a shoe having an inclined upper surface for receiving the thrust of a brake-block having a corresponding inclined surface, and the means for holding said inclined surfaces in contact, a standard extending from said brake-block, and having a shoulder thereon for holding in position a collar, the upper end of said standard being screw-threaded for the engagement of a nut for adjusting the downward movement of said standard for contacting a railway-track as specified.

7. In combination with a track-brake, a shoe having an inclined upper surface for receiving the thrust of a brake-block having a corresponding inclined surface, and the means for holding said inclined surfaces in elastic contact, a standard extending from said brake-block provided with a nut on its upper end, a spring supporting said nut and standard, said spring holding in position a spur gear-wheel located on the top of a hanger, and the means for operating said spur gear-wheel for the purpose as shown and described.

35 8. In combination with a track-brake, a shoe having an inclined upper surface for receiving the thrust of a brake-block having a corresponding incline, and the means for holding said inclined surfaces in elastic contact, a standard extending from said brake-block provided with a collar for receiving the thrust of a pair of rollers secured to a bell-crank lever and a spring for holding said standard suspended for the purpose, as specified.

45 9. In combination with a track-brake, a shoe having an inclined upper surface for receiving the thrust of a brake-block having a corresponding inclined surface, with friction-rollers between said inclined surfaces, and the means for holding said inclined surfaces in elastic contact with said friction-rollers, a standard extending from said brake-block which is provided with a collar for operating 50 a brake-shoe through the medium of a pair of rollers secured to independent arms located on a spring-actuated shaft and on opposite sides of said standard, a curved lever for operating said rollers through the medium of 55 appropriate rods and chains connected to the

opposite ends of a railway-car, for the purpose as shown.

10. In combination with a brake, a shoe having an inclined upper surface for receiving the thrust of a brake-block having a corresponding inclined surface, a hole within said brake-block having a spring and a plug therein, a standard extending from said brake-block provided with a bearing for receiving a pair of rollers for operating said standard, a spring and nut on the upper extremity of said standard for suspending the brake mechanism as specified.

11. In combination with a track-brake, independent shoes having inclined surfaces for receiving the thrust of a brake-block having a double inclined surface one brake-shoe operating when the car is going in one direction, and the other shoe when the car is going in the opposite direction, and the means for holding said double inclined surfaces in an elastic contact, a standard extending from said brake-block provided with a bearing-surface for receiving the thrust of a pair of rollers secured to a bell-crank lever for the purpose of operating said brake mechanism on a railway-rail as specified.

12. In combination with a track-brake, a brake-block having a double inclined surface for contacting independent brake-shoes, some 90 brake-shoes operating when the car is going in one direction, and the other shoes when the car is going in the opposite direction, said brake-shoes being connected to said brake-block by independent elastic connections, a 95 standard extending from said brake-block provided with a bearing-surface for receiving the thrust of a pair of rollers secured to a bell-crank lever for operating said mechanism as specified.

13. In combination with a track-brake, independent shoes having inclined surfaces for engagement with a brake-block which also has inclined surfaces, said surfaces held in contact through the medium of links and 105 springs, and the means for forcing said shoes in contact with a track; said shoes being adapted to operate when a car is moving in opposite directions, one brake-shoe operating when the car is going in one direction, and 110 the other shoe when the car is going in the opposite direction, without reversing said brake mechanism for the purpose as specified.

In testimony whereof we affix our signatures in presence of two witnesses.
